UNITED STATES PATENT OFFICE

EDWARD P. DANDRIDGE, OF SWARTHMORE, PENNSYLVANIA

CORN-EAR HOLDER

Application filed December 29, 1928. Serial No. 329,114.

This invention relates to a holding device for ears of corn and has for its primary object to provide, in a manner as hereinafter set forth, a means for holding an ear of corn in upright position so that the kernels thereof may be easily stripped or cut from the cob.

Another object of the invention is to provide in association with the means for holding an ear of corn in upright position, a receiver for the kernels of corn as they are removed from the cob.

The invention broadly contemplates the provision of a structure comprising a pair of tables one of which is in the form of a tray and is mounted to be tipped to discharge material therefrom, and a pair of opposed spiked members one of which is shiftable relative to the other and between and by which an ear of corn is designed to be gripped and held in vertical position. The kernels of the ear of corn as they are cut from the cob are received in the tray-like table top.

The invention will be best understood from a consideration of the following detailed description taken in connection with the accompanying drawing forming a part of this specification, with the understanding, however, that the invention is not confined to any strict conformity with the showing of the drawing but may be changed or modified so long as such changes or modifications mark no material departure from the salient features of the invention as expressed in the appended claim.

35 In the drawing:—

Figure 1 is a view in side elevation of the device embodying this invention, portions thereof being shown in section;

Figure 2 is a sectional view taken upon the line 2—2 of Figure 1;

Figure 3 is a sectional view taken upon the line 3—3 of Figure 1;

Figure 4 is a view in side elevation of the upper portion of the upright frame.

45 Referring to the drawing in detail wherein like numerals of reference indicate corresponding parts throughout the several views, the numeral 1 indicates generally the body of the cob holding device, the same being of elongated rectangular configuration and pro-

vided at each end with the side supporting feet 2 by means of which it may be supported upon a table or similar structure.

Intermediate the ends of the body there extends transversely thereof the raised platform portion 3 from the sides of which there extends upwardly the standards 4, these standards being connected at their upper ends by the cross member or yoke 5 which is pivotally secured at its rear edge by a hinge 6, to one of the standards in the manner shown. The yoke is thus mounted to be swung upwardly from its position upon the upper ends of the stands. Suitable hooks and eyes 7 are provided at each end of the yoke portion 5 to latch the same to the standards 4 in the manner shown so that the yoke may be secured against movement.

The platform 3 extending transversely of the body of the structure thus divides the same into a pair of tables indicated by the numerals 8 and 9 respectively. The table 8 at its side opposite the platform 3 is provided with suitable upstanding guards 10 which act to prevent ears of corn or empty cobs which may be stacked thereon from rolling therefrom.

At the opposite side of the raised portion of the platform 3 the table 9 has mounted thereon a tray 11 one end of which abuts against the platform 3 in the manner shown while at each side adjacent the opposite end there is mounted a hinged plate 12 which extends downwardly over the side of the table and has pivotal connection therewith as at 13 so that the end of the tray adjacent the platform may be swung upwardly to permit the dumping of kernels of the corn from the tray. To facilitate the tipping of the tray there is mounted at each side adjacent the free end thereof a lateral tongue or handle 14.

Rotatably mounted upon the top of the platform 3 centrally between the sides thereof is a disk or plate 15 from the central portion of which there extends upwardly a sharp pointed spike 16 and surrounding this spike and extending upwardly from this plate is a plurality of smaller shorter spikes 17.

Reciprocably or slidably extended through the yoke 5 of the upstanding structure is a shaft 18, the longitudinal center of which is aligned with the longitudinal center of the spike 16 of the plate 15 and in the lower end of this shaft is mounted a plate 19 carrying and having extending downwardly from the central portion thereof the relatively long sharpened spike 20 and the plurality of shorter spikes 21 surrounding the central spike.

The upper end of the shaft 18 is provided with a suitable handle 22 to facilitate grasping and actuating the shaft.

Extending transversely of the lower ends of the uprights 4 upon the side opposite the tray 11 is a shield plate 23 which extends a substantial distance upwardly and prevents kernels of corn falling from the cob which is mounted in upright position between and penetrated at the ends by the spikes 16, 17, 20 and 21, from falling back upon the table 8.

From the foregoing description it will be readily understood that in the use of this machine an ear of corn either raw or cooked is first placed in upright position upon the spike 16 of the lower rotatable disk 15 and the shaft 18, then lowered to position the spike 20 against the opposite end thereof. A forced further movement downwardly of the shaft 18 will then cause the spikes 16 and 20 to deeply penetrate the central portion or pith of the corn cob and at the same time will force the smaller spikes 17 and 21 into the cob about the center thereof. The cob is then firmly held in upright position to facilitate the working of a knife longitudinally of the face thereof to cut the kernels therefrom, rotation of the cob being accomplished by turning the handle 22 and shaft 18 which is controlled thereby. As the kernels are cut from the cob they will fall into the tray 11 and as the tray is filled the contents thereof may be dumped into a suitable dish or receiver placed at the end of the structure by grasping one of the members 14 and swinging the inner end of the tray upwardly. The table 8 may be employed for holding a number of ears of corn to be worked upon or the empty cobs of the ears from which the kernels have been removed.

Having thus described my invention, what I claim is:

In combination, a supporting structure and corn husking means mounted on said structure, said supporting structure comprising an elongated table, a storage bin on the table and extended inwardly from one end thereof, corn husking means mounted on the table adjacent said storage bin, said corn husking means comprising a vertical frame, a base, a lower cob engaging member rotatably mounted in the base, a cross bar hingedly mounted on the upper end of the frame, an upper cob engaging member rotatably mount-

ed in said cross bar, means for rotating said upper cob engaging member, locking means for holding the cross bar in rigid position on the frame and a tray hingedly mounted on the table and adapted to receive the corn removed from the cob.

In testimony whereof I hereunto affix my signature.

EDWARD P. DANDRIDGE.
